(57) **CLAIM**

The ornamental design for a dual chamber cosmetics container, as shown and described.

DESCRIPTION

FIG. 1 is an exploded perspective view of a dual chamber cosmetics container, showing my new design;

FIG. 2 is a closed perspective view of the dual chamber cosmetics container;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines shown in the drawings form no part of the claimed design.

The LAYRITE trademark forming part of the claimed design is a registered trademark of Layrite, LLC of California.
